(57) **CLAIM**

(21) Appl. No.: **29/147,101**

The ornamental design for a testing device of microphone,
as shown and described.

(22) Filed: **Aug. 23, 2001**

DESCRIPTION

(51) LOC (7) Cl. **14-01**

FIG. 1 shows a perspective view of the present design;
FIG. 2 shows a front elevational view of the present design;
FIG. 3 shows a rear elevational view of the present design;
FIG. 4 shows a left elevational view of the present design;
FIG. 5 shows a right elevational view of the present design;
FIG. 6 shows a top plan view of the present design;
FIG. 7 shows a bottom plan view of the present design; and
FIG. 8 shows the status of using of the present design.
The broken line showing of the microphones and headsets in
FIG. 8 is for illustrative purposes only and forms no part of
the claimed design.

(52) U.S. Cl. **D14/227**
